CLAIM

The ornamental design for a rotatable line transfer mechanism for a fishing reel, as shown and described.

DESCRIPTION

FIG. 1 illustrates a rear perspective view of a rotatable line transfer mechanism for a fishing reel;

FIG. 2 illustrates a rear view thereof;

FIG. 3 illustrates a front view thereof;

FIG. 4 illustrates a right-side view thereof;

FIG. 5 illustrates a left-side view thereof;

FIG. 6 illustrates a top view thereof; and,

FIG. 7 illustrates a bottom view thereof.

The broken lines showing parts of the rotatable line transfer mechanism, the fishing reel, fishing rod and fishing line represent unclaimed matter and do not form part of the claimed design.
